Primary Examiner — John Windmuller*Assistant Examiner* — Luqman McNeil(74) Attorney, Agent, or Firm — R. Tracy Crump(57) CLAIM

I claim the ornamental design of a tactical jacket, as shown and described.

DESCRIPTION

FIG. 1 is a perspective view of a tactical jacket showing my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

For illustrative purposes, the tactical jacket is shown in the drawings with the left arm raised. The arms of the tactical jacket are symmetrical. The broken lines in the figures represent stitch lines that form part of the claimed design.
